Patented May 11, 1926.

UNITED STATES PATENT OFFICE.

JAMES G. ROSS, OF SEATTLE, WASHINGTON, ASSIGNOR OF ONE-HALF TO WILLIAM R. SCOTT, OF SEATTLE, WASHINGTON.

DIRECTION SIGNAL.

Application filed November 21, 1923. Serial No. 676,115.

This invention relates to an improved direction signal of the general character shown in Patent No. 1,449,297, issued to me March 20, 1923, and seeks, among other objects, 5 to provide a signal embodying an improved mounting for the indicators of the device so that said indicators may be shifted manually without appreciable effort.

The invention seeks, as a further object, 10 to provide a signal wherein the indicators will be automatically locked when projected and likewise automatically locked when retracted.

And the invention seeks, as a still further object, to provide a signal wherein, when the indicators are projected, the signal lamps upon the indicators will be energized while, when the indicators are retracted, said lamps will be extinguished.

20 Other and incidental objects will appear hereinafter.

In the drawings:

Figure 1 is an elevation showing my improved signal mounted at the base of the 25 wind shield of a motor vehicle,

Figure 2 is an edge elevation of the front plate of the signal casing,

Figure 3 is an elevation of the signal casing, the front plate being removed,

30 Figure 4 is a longitudinal sectional view through the device,

Figure 5 is a detail elevation of one of the indicator lamp housings, one section of the housing being removed,

35 Figure 6 is a detail sectional view on the line 6-6 of Figure 1, looking in the direction of the arrows,

Figure 7 is a detail sectional view on the line 7-7 of Figure 3, looking in the direction 40 of the arrows,

Figure 8 is a detail sectional view on the line 8-8 of Figure 4, looking in the direction of the arrows, and

45 Figure 9 is a fragmentary elevation particularly showing the spring lugs employed for yieldably locking the indicators of the device.

In carrying the invention into effect, I employ an oblong casing 10, rectangular in 50 cross section, and closing the casing at its forward side is a removable front plate 11. Formed in the side walls of the casing are transverse slots 12 and extending across the

casing between said slots are rollers comprising end rollers 13 and a center roller 14. 55 These rollers are preferably rubber covered and, as brought out in Figure 3, said rollers are formed at their ends with trunnions journaled in the slots 12, the rollers being, of course, removable at the forward side of 60 the casing. Formed in the roller 14 are, as best shown in Figures 7 and 8, spaced annular grooves 15, and resting upon all of said rollers are indicators designated for convenience at 16 and 17 respectively. The side 65 walls of the casing are further provided with transverse slots 18 somewhat shorter than the slots 12 and extending across the casing between said slots are rollers 19 and 20 bearing against the forward sides of the indicators. These rollers are similar to the rollers 13 and 14, being provided at their ends with trunnions journaled in the slots 18, and formed on the front plate 11 of the casing 70 near the edges thereof are pairs of lugs 21 adapted to removably fit in said slots to bear against said trunnions for retaining the rollers in place. Thus, the indicators will be confined between the rollers 13 and 14 at 75 one side of the casing and the rollers 19 and 20 at the opposite side of the casing to be supported by said rollers for free longitudinal movement. Extending between the back wall of the casing and the plate 11, near the ends of the casing, are rollers 22 80 bearing against the inner edges of the indicators for guiding said indicators in their longitudinal movement. These rollers are similar to the other rollers used and are provided at their ends with trunnions journaled through the back wall of the casing 85 and through said plate. At their forward sides, the indicators are equipped with double-faced yieldable wedging members 23 and 24 respectively to cooperate with the 90 rollers 19 and 20. As will be seen, when the indicators are shifted outwardly to project at the ends of the casing, the outer inclined portions of said wedge members will ride beneath said rollers for limiting the indicators in their outward movement while, when the indicators are retracted, the inner inclined portions of said members will, as 95 shown in Figure 3, ride beneath said rollers for limiting the indicators in their inward movement. However, to prevent possible 100

- 2 binding of the indicators when shifted inwardly, stops 25 are provided upon the top and bottom walls of the casing for engagement by the inner ends of the indicators. 5 Preferably, the indicator 16 is provided at its inner edge with a longitudinal slot 26 while the indicator 17 is provided at its inner edge with a tongue 27 fitting in said slot to slidably connect the indicators with 10 each other.

Mounted upon the indicators at their outer ends are preferably arrow-shaped signal casings 29 pointing toward the right and left, respectively. As brought out in Figure 6, the signal casings are each formed of mating side sections having marginal flanges 30 fitting one within the other connecting the sections, while the side walls of the sections are, as shown in Figure 5, 15 cut away to define window openings 31 arrow-shaped in outline. Overlying said openings are transparencies 32 secured against said side walls by lugs 33. The signal casings are secured upon the outer ends of the indicators in any suitable manner and mounted in the outer terminals of the indicators are lamp sockets 34. These 20 sockets may be of any approved design, and removably mounted in said sockets are signal lamps 35. Extending longitudinally of the indicators from the inner ends of the sockets 24, are channels 36 terminating in recesses 37 and set into the outer side walls of said recesses are, as shown in detail in Figure 8, insulating blocks 38. Mounted upon said blocks are contact blades 39 and connected to said blades are wires 40 extending through the channels 36 to corresponding terminals of the sockets 34, it 25 being noted that the blades are positioned to pass freely through the grooves 15 on the roller 14 when the indicators are shifted. Connected to the other corresponding terminals of said sockets are wires 42 electrically grounded to the indicators 16 and 17. Set into the back wall of the casing are, 30 as shown in detail in Figure 8, insulating blocks 43 on which are mounted pairs of spring contact fingers 44 and connected to said pairs of fingers is a feed wire 45. Thus, as will be seen, when the indicator 16 is shifted outwardly for signaling an intention of the driver to turn to the right, the contact blade of said indicator will be moved 35 to engage between one of the pairs of fingers 44 for energizing the lamp within the signal casing of said indicator so that the signal casing will, accordingly, be illuminated and will thus be readily visible. 40 Similarly, when the indicator 17 is shifted outwardly for indicating an intention to turn to the left, the signal casing of said indicator will be illuminated, the device accordingly being highly efficient.

65 Formed in the front plate 11 of the casing

are, as shown in Figure 1, parallel longitudinal slots 46 at the ends of which are pairs of spring lugs 47 and extending freely through said slots are handles 48 screwed into the indicators 16 and 17. The shanks of these handles are disposed to ride between the pairs of lugs 47 so that when the indicators are retracted the pairs of lugs at corresponding ends of the slots will thus automatically lock the indicators in retracted 75 position while, when the indicators are projected, the pairs of lugs at the opposite corresponding ends of the slots will frictionally engage the shanks of the handles for automatically locking the indicators projected. 80 In use, the handles are, of course, grasped for shifting the indicators and, as will be appreciated, only a slight pressure on the handles will be required to overcome the tension of the spring lugs 47. As suggested 85 in Figure 1, the device is preferably mounted upon a motor vehicle at the base of the wind shield thereof so that the handles may be readily reached from the driver's seat and, of course, the indicators are of 90 such length that, when said indicators are projected, the indicators will extend at the sides of the vehicle so as to be readily visible.

Having thus described the invention, what 95 is claimed as new is:

1. A direction signal including a casing, indicators shiftable longitudinally within the casing to project at the ends thereof, rollers journaled within the casing and 100 bearing against opposite side faces of the indicators whereby to confine the indicators to rectilinear paths, and yieldable wedging members on the indicators between some of the rollers adapted to engage said rollers 105 whereby to limit the longitudinal movement of the indicators.

2. A direction signal including a casing, rollers journaled therein, indicators shiftable longitudinally within the casing to project at the ends thereof, and confined by and between said rollers, and other rollers journaled within the casing near its ends to bear against the inner edges of the indicators and engaging end portions thereof 115 to limit their inward movement.

3. A direction signal including a casing having a front plate provided with longitudinal slots and formed at the ends of said slots with pairs of spring lugs, indicators 120 slidably mounted in the casing and shiftable outwardly to project at the ends of the casing as well as inwardly housed within the casing, and handles for the indicators projecting through said slots, the handles being movable between said pairs of lugs for yieldably locking the indicators at the end of their movement in opposite directions.

4. In a direction signal, the combination 125

of a casing having a wall thereof provided with a slot and formed at one end of said slot with a pair of spring lugs integral with said wall, an indicator shiftable in the casing to project at one end thereof, and a handle fixed to the indicator to freely project through said slot and movable between

said pair of lugs to be yieldably gripped thereby for locking the indicator against movement.

In testimony whereof I affix my signature.

JAMES G. ROSS. [L. s.]
